Inventor:
A. W. Wilcox

United States Patent Office.

A. W. WILCOX, OF WORCESTER, MASSACHUSETTS.

Letters Patent No. 62,683, dated April 9, 1867.

IMPROVEMENT IN MELODEONS.

The Schedule referred to in these Letters Patent and making part of the same.

KNOW ALL MEN BY THESE PRESENTS:

That I, A. W. WILCOX, of the city and county of Worcester, and Commonwealth of Massachusetts, have invented certain new and useful Improvements in Melodeons; and I do hereby declare that the following is a full, clear, and exact description of the same, reference being had to the accompanying drawings, forming a part of this specification, in which—

Figure 1 represents a perspective view of so much of a melodeon as is necessary to illustrate my invention.

Figure 2 represents a perspective view of the parts shown in fig. 1, with the swell box removed; and

Figure 3 represents a vertical cross-section of fig. 1, looking in the direction indicated by the arrow, fig. 1.

In the drawings, A represents the table or board upon which the reeds *a* are placed, and below which are arranged the valves *b*, held up by springs *c*, and operated by levers connected to cords *d* in the well-known manner. Above the reeds is arranged the chamber, B, closed at the top by a valve, *3'*. Said chamber is also closed at the bottom by a valve, *1'*, while the opening from the swell box C to the reeds below the chamber B is closed by a valve, *2'*. These valves are operated by their respective stops, 1, 2, and 3, which, when drawn out, open the valves, and close them when pushed back. By the combination and arrangement of the above valves with the chamber B, within the swell box C, a great variety and quality of tones can be produced. For instance, when valve *1'* is open, only then a tone called oboe or hautboy is produced; when valves *1'* and *3'* are open, a trumpet tone is produced; and when only valve *2'* is open, a tone is produced resembling the clarionet. In addition to the above-named tones, the quality may be varied by changing the valves into other combinations. The swell box C has two valves, D and E, which are both opened by depressing lever F so as to cause it to swing upon its pivot *e*, thereby opening valve E, which swings down, while valve D is elevated by the connection G, (see red lines, fig. 3.) *f* is an air-hole which forms a communication between the interior of chamber B and the swell box C.

Having described my improvements in melodeons, what I claim as new, and of my invention, and desire to secure by Letters Patent, is—

1. The combination with chamber B of the valves *1'*, *2'*, and *3'*, for the purposes stated.
2. The combination with chamber B and swell box C, of the valves *1'*, *2'*, and *3'*, and D E, arranged for joint operation as set forth.

A. W. WILCOX.
